Term of patent 14 years

Int. Cl. D23—04

U.S. Cl. D23—139

FIG. 1 is a front perspective view of an industrial radiator for use in low pressure water cooling systems showing my new design, the opposite side being identical except the upper portion as indicated in FIGS. 2 and 3.

FIG. 2 is a rear elevational view thereof.

FIG. 3 is a top plan view thereof, but with the view being on a reduced scale.

I claim:

The ornamental design for an industrial radiator for use in low pressure water cooling systems, substantially as shown and described.
